JOHANNES HUBERT ANTON MIALARET, OF MAASTRICHT, NETHERLANDS.

PROPORTIONAL COMPASSES FOR PERSPECTIVE DRAWING.

1,193,914.

Specification of Letters Patent.

Patented Aug. 8, 1916.

Application filed May 16, 1914. Serial No. 839,063.

To all whom it may concern:

Be it known that I, JOHANNES HUBERT ANTON MIALARET, a subject of the Queen of the Netherlands, and residing at 11 5 Breede straat, Maastricht, the Netherlands, have invented certain new and useful Proportional Compasses for Perspective Drawing, of which the following is a specification.

This invention relates to proportional or 10 reducing compasses for perspective drawing, by which from a given plan and elevation, a perspective drawing can be made without any calculation being required therefor. The compasses comprise two 15 pairs of legs movable in the manner of shears; according to the present invention the length of the individual legs can be varied independently of each other.

The proportional compasses according to 20 this invention and their application in practice are illustrated on the accompanying drawing.

Figures 1-3 show problems in perspective drawing which can be solved with the

$$\frac{aC}{AY} = \frac{SC}{SY} = \frac{SC}{SC+CY} = \frac{\text{distance of the eye from the picture plane}}{\text{distance of the eye from the picture plane} + \text{distance of the point behind the picture plane.}}$$

Calling the distance of the eye from the 50 picture plane D^i (hereinafter shortly referred to as "distance") and the distance behind the picture plane P^r (hereinafter shortly referred to as "depth"), the foregoing proportion will be equal to

$$\frac{D^i}{D^i+P^r}$$

Upon this proportion, which gives the reduction for a straight line parallel to the 60 picture plane, the practical use and arrangement of the proportional compasses according to the present invention is based. For each portion of the same straight line parallel to the picture plane there will be the 65 same reduction, the latter, however, being different for each other parallel line in accordance with the varying distance behind the picture plane or depth.

In Fig. 2 the plan and elevation of the 70 shed shown in Fig. 1 are drawn, hereafter a perspective drawing (see Fig. 3) is to be made. In Fig. 2, $G G$ is the ground-line of an assumed picture plane, C^i the projection of an assumed center of the picture upon 75 $G G$ and $C^i D$ the trace of the dividing

proportional compasses according to this invention without any calculation being required. Figs. 4 and 5 represent respectively a side elevation and a front elevation of the proportional compasses when closed. Fig. 6 represents one body piece of the compass 30 looking at the inner face, with leg extended. Fig. 7 is a cross section according to the line $V-W$ in Fig. 5.

In Fig. 1 a shed or barn is shown, which is to be drawn on the vertical picture plane 35 $P P$. S is the center of projection or the point of sight, C the center of the picture or the center of vision, $H H$ the horizontal plane through the eye and $D D$ the plane dividing the infinite space for the spectator 40 in a right hand portion and a left hand portion. A is assumed to be a point in the height of the eye on the wall edge $B F$ of the shed, $A Y$ a perpendicular drawn from A upon the plane $D D$ and a the perspective 45 of the point A . $C Y$ then is the distance of A behind the picture plane and it may be determined from the following formula:

plane $D D$. The lines $G G$ and $C^i D$ then can serve for measuring for each point in the plan the distance behind the picture plane and the distance to the right or to the left from $D D$. 80

In the elevation the assumed horizon $H H$ can serve for measuring for every point the height above or depth under the horizon.

After having chosen a certain length D^i for the distance, the perspective of the shed 85 could be determined by calculation. For this purpose first the lines $H H$ and $D D$ (see Fig. 3) are drawn, thereupon the length of the line C, a , is calculated by reducing the length of the line $A^i Y^i$ of Fig. 90 2 according to the proportion

$$\frac{D^i}{D^i+P^r} \left(\text{in this case thus } \frac{CS}{CS+A^iZ} \right).$$

This calculated length is set off from C 95 to the right on $H H$, thereby obtaining the point a . Now drawing a perpendicular through a and setting off the lines $A B$, $A F$ and $A E$ from Fig. 2 reduced in the same proportion as $A^i Y^i$ from a on said 100 perpendicular, the required points b, f and e of the wall edge $b f$ will be obtained.

In a similar way for each other wall edge the perspective reducing could be determined by calculation; hereby the reducing proportion

$$5 \quad \frac{D^i}{D^i + P^r}$$

varies for each different depth.

The present invention now has for its 10 object to replace the calculation of these reducing proportions by a simple mechanical reduction. When of a pair of proportional compasses one pair of legs the length D^i and the other pair of legs the length $D^i + P^r$ 15 is given (see Fig. 2), then all distances taken between the points of the longer pair of legs will be reduced according to the proportion

$$20 \quad \frac{D^i}{D^i + P^r}$$

between the points of the shorter pair of legs. With such proportional compasses the reductions otherwise to be calculated can 25 thus be determined by a simple mechanical operation.

In Figs. 2 and 3 this is shown for the line A F. One pair of legs of the compasses is made equal to D^i and the other pair equal 30 to $D^i + P^r$. Between the points of the longer pair of legs the line A F from Fig. 2 is taken; between the shorter pair of legs this line is reduced according to the proportion

$$35 \quad \frac{D^i}{D^i + P^r}$$

thus giving the perspective length a f. This length is set off in Fig. 3, after having previously ascertained the point a from C out 40 by reducing A¹ Y¹.

According to this invention the legs of the proportional compasses are arranged in such a way that the lengths of the individual legs can be varied independently of 45 each other.

In the embodiment of the invention shown in Figs. 4-7 the compasses consist of two body pieces I, pivotally connected by means of a screw R with wing nut T and pressure 50 spring U. Each body piece is provided with two slidable legs J and K. On the legs J (the distance legs) the distance D^i and on the legs K (the depth legs) the length $D^i + P^r$ is set off. By employing a 55 tube L or other telescoping means, the legs K can obtain a considerably greater length than the legs J. One of the body pieces I moreover contains an adjustable distance indicator M for the purpose of indicating 60 from the pivot of the compasses the distance D^i on one of the legs K. The distance indicator is provided with a plurality of center holes O and at its outer extremity with a center hole N, the distance between the pivot 65 of the compasses and said center hole N

being made equal to the "distance". From this center hole N now the depth P^r is added upon the legs K. The telescoping tubes L and the lower slidable legs J are secured in the required position by means of the screws 70 4, and the legs K which slide within the tubes L are secured therein by the screws 5.

As stated hereinbefore by perspective drawing the reducing proportion

$$75 \quad \frac{D^i}{D^i + P^r}$$

continually varies with the changing of the depth P^r , the distance D^i , however, always remaining unchanged for the same drawing. 80 With the distance indicator now the advantage is obtained that the varying reducing proportion can in a very simple way be fixed by every time setting off the changed depth from the center hole N upon 85 the legs K.

The groove containing the distance indicator is provided with a slot on the inside of the body piece I, so that in case of a short distance one of the center holes O 90 may be used instead of the center hole N. The distance indicator M is further provided with a $\frac{1}{8}$ or $\frac{1}{16}$ inch scale.

The inside view (Fig. 6) shows a number of engraved division lines for the purpose of enabling the setting out of the distance on the legs J and on the distance indicator M from the inaccessible pivot of the compasses.

The body pieces I are provided with a 100 number of holes Q, each of which may be used as pivot hole for the compasses. In this way the range of the compasses is enlarged, which is of importance e. g. when the object to be drawn is located far behind 105 the ground line.

The setting off of a dimension such as A¹ Z of Fig. 2 from the center hole N on a depth leg K of the compasses may be effected 110 by means of ordinary compasses.

In case the plans are, however, of such a size that the depth legs K cannot be made sufficiently long for the depth dimensions then the taken dimension is every time set off in a reduced state, thereby employing 115 ordinary reducing compasses as auxiliary compasses. In such cases a simple reduction is chosen, such as $\frac{1}{2}$, $\frac{1}{3}$, $\frac{2}{3}$, etc., whereby the distance legs J too are then to be adjusted for $\frac{1}{2}$, $\frac{1}{3}$, $\frac{2}{3}$, etc., of the distance. In 120 this way the legs of the compasses will have the correct proportion again for setting out the dimensions in the picture.

When the dimension of the assumed distance surpasses the greatest possible or desirable length of the distance legs J of the compasses suitable reductions such as $\frac{1}{2}$, $\frac{1}{3}$, or the like are similarly employed.

In very small plans such as may for example be found in books the distance and 130

the depth are by means of such auxiliary compasses set off on the legs J and K in an enlarged scale.

Such auxiliary compasses, serving to make 5 the proportional compasses according to this invention adapted for all practical purposes and thus for drawings of the most varying sizes, may be of a very simple construction, as said compasses, though they 10 must be of a somewhat large size, are to reduce or to enlarge in a few fixed proportions only.

The proportional compasses for perspective drawing may be of any suitable construction 15 provided that the length of one pair of legs can be made equal to the dimension of the distance and the length of the other pair equal to the dimension of the distance plus the depth.

Having now described my invention, what 20 I claim as new and desire to secure by Letters Patent is:—

1. Proportional compasses for perspective drawing comprising, in combination, two 25 body pieces, a screw and nut for pivotally connecting said body pieces together, two pairs of legs one of each pair being slidably contained in each body piece, and means for locking the individual legs after they have 30 been adjusted, independently of each other.

2. Proportional compasses for perspective drawing comprising, in combination, two body pieces, a screw and nut for pivotally connecting said body pieces together, each of 35 said body pieces having a plurality of holes adapted to receive the pivot of the compasses, two pairs of legs one of each pair being slidably contained in each body piece, and means for locking the individual legs 40 after they have been adjusted, independently of each other.

3. Proportional compasses for perspective drawing comprising, in combination, two body pieces, a screw and nut for pivotally 45 connecting said body pieces together, two pairs of legs one of each pair being slidably contained in each body piece, a distance indicator slidable in one body piece for indicating the distance from the pivot of the 50 compasses on the leg contained in that body piece and means for locking the individual legs after they have been adjusted, independently of each other.

4. Proportional compasses for perspective

drawing comprising, in combination, two 55 body pieces, a screw and nut for pivotally connecting said body pieces together, two pairs of legs one of each pair being slidably contained in each body piece, a distance indicator slidable in one body piece having 60 a center hole on its outer extremity for setting off therefrom a given dimension (the distance from the point to be projected to the picture plane) on the leg contained in that body piece and means for locking the 65 individual legs after they have been adjusted, independently of each other.

5. Proportional compasses for perspective drawing comprising in combination two body pieces one of which is provided with a 70 groove and a slot on the inside in connection with the groove, a screw and nut for pivotally connecting the said body pieces together, two pairs of legs one of each pair being slidably contained in each body piece, 75 a distance indicator slidable in the groove, and having a center hole on the outer extremity also having a plurality of center holes visible through the slot and which are adapted to be employed instead of the 80 center hole on the outer extremity of the distance indicator for setting off a given dimension (the distance from the point to be projected to the picture plane) on one of the legs, and means for locking the individual 85 legs after they have been adjusted, independently of each other.

6. Proportional compasses for perspective drawing comprising, in combination, two body pieces, a screw and nut for pivotally 90 connecting said body pieces together, each of said body pieces having a plurality of holes and scale marks, and one of said body pieces being provided with a groove and a slot in the inside, two pairs of legs, a distance indicator slidable inside the groove, and provided with scale marks and having a center hole on its outer extremity, also having a plurality of center holes equidistantly arranged over its length, and means 95 100 for locking the individual legs after they have been adjusted, independently of each other.

In testimony whereof I have signed my name to this specification in the presence of 105 two subscribing witnesses.

JOHANNES HUBERT ANTON MIALARET.
